TOY

David Silvette, Henrico County, Va.

Application February 21, 1939, Serial No. 257,592

2 Claims.

(Cl. 46—1)

This invention relates to toys and more particularly to a device of amusement and personal gratification of small children.

One of the objects of this invention is the provision of a toy that may be used in conjunction with containers or the like. It is often the custom of merchants to provide a novel toy that may be used in connection with their products, and one of the objects of this invention is the provision of a toy that may be used in connection with a container.

Another object of this invention is the provision of a toy adapted to house a projectile adapted to be ejected therefrom.

Other objects and features will more fully appear from the following description and accompanying drawing, in which:

Fig. 1 is a sectional perspective of the toy; Fig. 2 a top plan view; Fig. 3 a side view, and

Fig. 4 a top view of the projectile.

Referring to the drawing a housing 1 is formed by a base 2 provided with a circumferential side 3 having nibs 4 extending toward said base. A groove 5 is formed by said sides.

A projectile 6 is adapted for disposition in said housing; being held in position by said nibs, and an ejector 7 is disposed between said base and projectile. When stress is exerted on said ejector,

in proper fashion, the projectile is thereby forced from the housing.

The toy is shown secured to a container 8, and Fig. 4 discloses the projectile upon which may be printed or shown a picture.

The projectile may be constructed in ovoidal fashion so that only a few nibs will contact it, or it may be constructed as illustrated.

Having described the invention, what is claimed is:

1. A housing, disposed upon a container, consisting of a base provided with a circumferential groove; a plurality of nibs on said housing; a projectile disposed in said housing above said base and adapted to be secured by said nibs, and means between said base, and projectile adapted to exert a stress upon the latter member to cause its ejection from said housing.

2. A container, a housing disposed upon said container, said housing consisting of a base provided with a circumferential groove, a plurality of nibs on said housing; a projectile disposed in said housing above said base and adapted to be secured by said nibs, means consisting of an ejector disposed between said base and projectile; said ejector being adapted to force said projectile from said container and said ejector means.

DAVID SILVETTE.
